TROTLINE FISHING REEL

Flavil H. Griggs, Friendship, Tenn.
Filed Dec. 24, 1963, Ser. No. 333,057
8 Claims. (Cl. 43—27.4)

This invention relates to a reel for use in trotline fishing, and more particularly to a reel for use in a boat for setting or taking up a trotline.

The conventional method of setting a trotline from a boat is to attach one end of the line to an anchor or support on the bank of the body of water and proceed from the bank in the boat, paying out the trotline as the boat progresses away from the bank and anchoring the bitter end of the trotline out in the body of water. As the trotline is payed out, hooks are attached to the line at spaced intervals by short leaders so that a single trotline, when set, will support a relatively large number of individual fish hooks spaced along the length of the line.

In taking up a trotline which has been previously set as above described, it is conventional to proceed in the boat to the end of the trotline farthest from the bank or anchor, lift the end into the boat and, by heaving in on the trotline, move the boat along the line toward the bank. As the line is heaved in, the individual leaders and hooks are removed from the trotline and stored in any convenient manner to prevent the hooks from becoming entangled with each other and with the leaders. This, obviously, is a slow and difficult task which is accomplished only at appreciable risk to the fisherman.

Although numerous attempts have been made in the past to devise a reel mechanism which may be employed to set or take up a trotline with the hooks attached, these attempts have not been successful, insofar as I am aware, and the prevailing practice still remains as that outlined above. It is, therefore, an object of this invention to provide a new and improved reeling device for use in a boat for setting and taking up trotlines with the hooks attached to the trotline.

Another object of the invention is to provide such a reeling device for use in a boat for setting and taking up trotlines which will automatically release the hooks attached to the trotline as the trotline is unwound from the reel.

Another object of the invention is to provide such a reeling device for use in a boat for setting and taking up trotlines and having means for preventing hooks attached to the trotlines from becoming fouled upon the gunwale of the boat upon paying out or reeling in the trotline.

Another object of the invention is to provide such a reeling device for use in a boat for setting and taking up trotlines which is easy to operate and which requires only one man in the boat to set or take up the trotline.

Another object of the invention is to provide such a reeling device for use in a boat for setting and taking up trotlines which is easy and safe to operate and which may be employed to store trotlines when not in use.

In the attainment of the foregoing and other objects of the invention, an important feature of the invention resides in the employment of a reel mounted for rotation about a vertical axis and having a bottom flange which includes a first substantially radial section and a second substantially conical section extending outwardly and downwardly. A plurality of pins are mounted on the outer surface of the conical section of the flange and project upwardly and outwardly therefrom in position to receive and support hooks mounted upon a trotline being wound up on the reel. A guide is provided to lift and guide a trotline and the attached hooks over the gunwale of the boat as the trotline is being wound upon or unwound from the reel. The guide includes an elongated arm

2

having one end pivotally mounted beneath the reel for limited rotation in a horizontal plane and a chock mounted on the other end of the arm to support the trotlines and hooks.

5 The pegs mounted in the lower flange are of such size as to be loosely received in the U-shaped portion of the fish hooks, and are inclined outwardly so that, upon paying out of the trotline, the hook will readily slip off the end of the pegs and automatically be released and payed out with the trotline, with the guide serving to prevent the hook from becoming fouled upon the boat as the line is payed out.

10 Other objects and features of the invention will become more apparent by reference to the following specification taken in conjunction with the accompanying drawings in which:

15 FIGURE 1 is a top plan view of a reel constructed in accordance with this invention and shown mounted in the bow of a boat;

20 FIGURE 2 is a side elevation of the device as shown in FIGURE 1;

25 FIGURE 3 is a fragmentary sectional view taken on line 3—3 of FIGURE 1 showing the means for supporting the reel and guide; and

30 FIGURE 4 is a sectional view taken on line 4—4 of FIGURE 3 more clearly showing the guide arm and its support means.

35 Referring now to the drawings in detail, a trotline reeling device according to the present invention, indicated generally by the numeral 10, includes a reel 12 mounted for rotation about a vertical shaft 14 mounted on a substantially flat base member 16. The reel 12 includes a cylindrical drum 18 suitably supported on hub 20 by integrally formed disc 22. An annular flange 24 extends radially from the top of drum 18, and a flange 26, having a first radially extending portion 28 and a second downwardly and outwardly, substantially conical shaped portion 30, extends outwardly from the bottom of drum 18. Hub 20 is provided with a first bore 32 to rotatably receive shaft 14, and a counterbore 34 to receive bearing 36 to minimize frictional resistance to rotation of the reel. A handle 40 is secured, as by screws 42, to disc 22 to facilitate manual rotation of the reel. A plurality of pins 44 are mounted on section 30 of flange 26, and project outwardly and upwardly from the outer surface thereof, with the pins terminating at a point below the upper surface of section 28 of flange 26.

40 A trotline guide member, indicated generally by numeral 50, has an elongated arm 52 having one end pivotally mounted to base 16, as by bolt 54 and nut 56, at a point beneath reel 12 near shaft 14. Arm 52 projects outward from beneath reel 12 and supports a chock 58 mounted on its upper surface near the end thereof to support and guide a trotline 60 and the depending leaders 61 and hooks 62 over the gunwale of a boat as the trotline is reeled in or payed out as seen in FIGURES 1 and 2. Anti-friction means, such as wheels 64, are provided on arm 52 near the outer end thereof, to lend vertical support to the projecting end of the guide means and to facilitate pivotal movement about bolt 54. Wheels 64 engage and roll upon a track 66 formed on base 16.

45 As shown in FIGURE 3, chock 58 is formed with surface discontinuities having a relatively large radius, as at 68, 70, to permit fish hooks to be drawn through the chock without becoming fouled. Also, the chock is preferably formed from a relatively light weight material, such as a synthetic resin material, having a hard, smooth outer surface to eliminate the possibility of fish hooks biting into the surface as they are moved through the chock.

50 To use the reel device described above, a trotline is made up with the fish hooks and leaders attached, and

wound upon drum 18 with the successive hooks and leaders being carried forward in the direction of rotation of the reel and the hook placed over the appropriate peg 44. The device is then placed in a boat and secured in position, as by hinge members 72, with the base and reel in a substantially horizontal position and with chock 58 projecting over and outboard of the gunwale of the boat. The outboard end of the trotline is then passed through the chock and firmly secured to a suitable anchor on the bank, and the boat is moved away from the bank with the reel permitted to run free to pay out the trotline and hooks as the boat proceeds. As best seen in FIGURE 3, as the trotline draws a leader out through the chock, the hook attached to the end of the leader will merely slide off the peg and be drawn through the chock with the trotline into the water.

To take up a trotline using the reel device herein described, the end of the trotline most remote from the bank is passed over the chock and attached to the drum and the operator rotates the reel by grasping and manually turning handle 40 with one hand. As the operator continues to rotate the reel to wind the trotline on the drum, chock 58 lifts the trotline and hooks clear of the side of the boat and directs the line substantially horizontally onto the reel. As a hook passes through chock 58, the operator picks up the hook with his free hand, leads it forward, and places it on the appropriate peg 44 while continuing to rotate the drum with the other hand. Thus, the fisherman, by rotating the reel, simultaneously winds the trotline on the drum and propels the boat toward the bank where the trotline is anchored, leaving the other hand free to place the hooks on the appropriate pegs as they pass through the chock. No problem is presented in maneuvering the boat since the guide is pivotally mounted beneath the reel and will always assume the appropriate position, within reasonable limits, with respect to the trotline regardless of the direction in which the boat is heading.

Fish hooks which are placed on the pegs 44 will lie flat against the conical surface portion of the bottom flange thereby eliminating the tendency of the hooks to tumble and become fouled as the other trotline is unreeled. Also, the outer portion of the flange extends beyond the pegs to act as a guard for the hooks to permit handling of the reel without danger from the hooks so that the reel may be removed from the shaft and employed to safely store trotlines.

While I have disclosed and illustrated a preferred embodiment of my invention, I wish it understood that I do not intend to be restricted solely thereto, but that I do intend to cover all embodiments thereof which would be apparent to one skilled in the art and which come within the spirit and scope of my invention.

I claim:

1. A device for use in setting and taking up trotlines comprising a reel having a drum portion upon which a trotline may be wound, a radially extending flange at one end of said drum, a flange at the other end of said drum having a first radially extending portion and a second substantially frusto-conical portion extending outwardly and downwardly from said first portion, and a plurality of pin members mounted on the other surface of said second portion and extending outwardly and upwardly therefrom, whereby fish hooks attached to the ends of leaders depending from a trotline being wound upon said reel

may be placed on said pegs for storage, said pins being positioned to permit fish hooks stored thereon to slide therefrom upon unwinding of the trotline.

2. The invention according to claim 1 including supporting means mounting said reel for rotation, and handle means for manually rotating said reel on said supporting means.

3. The invention according to claim 2 wherein said support means includes a base member and shaft means supported by and extending upwardly from said base for removably supporting said reel for rotation in a substantially horizontal plane.

4. The invention according to claim 3 including guide means for directing a trotline in a substantially horizontal line onto said reel.

5. The invention according to claim 4 wherein said guide means includes an elongated arm pivoted at one end of said base member at a point beneath said reel when said reel is mounted on said vertically extending shaft for limited rotation within a horizontal plane, and chock means on the other end of said arm and extending upwardly therefrom to support a trotline being wound upon or unwound from said reel.

6. The invention according to claim 5 including means vertically supporting said elongated arm at a point intermediate the pivot point and said chock while permitting rotation of said arm about said pivotal support.

7. A trotline reel comprising a base member, a shaft extending upward from the base, a reel removably mounted on said shaft for rotation in a substantially horizontal plane, said reel having top and bottom radially extending flanges, handle means on said reel for manually rotating said reel with respect to said shaft, a plurality of circumferentially spaced pins on said bottom flange for releasably retaining fish hooks attached to the ends of leaders depending from a trotline wound upon said reel, and guide means for directing a trotline and the depending leaders and hooks over the gunwale of a boat when said reel is employed to set or take up a trotline.

8. A trotline reel for setting, taking up, or storing trotlines comprising a base member, shaft means supported by and extending upwardly from said base, a reel removably mounted for rotation on said shaft, said reel including top and bottom radially extending flanges, means on the bottom flange for receiving and releasably retaining fish hooks attached to leaders depending from a trotline being wound upon said reel in position to be released as the trotline is unwound from said reel, and guide means for directing a trotline and the dependent leaders and hooks over the gunwale of a boat when said reel is employed to set or take up a trotline, said guide means including a laterally extending arm pivotally mounted at one end to said base beneath said reel for limited rotation in a horizontal plane, and chock means mounted on the other end of said arm for supporting and guiding the trotline.
